CLAIM

The ornamental design for a monocular telescope with integrated laser range finder, as shown and described.

DESCRIPTION

FIG. 1 is a front, left perspective view of a monocular telescope with integrated laser range finder according to my novel design;

FIG. 2 is a left side view thereof;

FIG. 3 is a right side view thereof;

FIG. 4 is a top view thereof;

FIG. 5 is a rear view thereof; and,

FIG. 6 is a front view thereof.

The broken lines are for illustrative purposes only and form no part of the claimed design.
